UNITED STATES PATENT OFFICE.

THOMAS TOMNEY McILRAITH, OF COLCHESTER, ENGLAND.

VALVE GEAR FOR INTERNAL-COMBUSTION ENGINES.

Application filed August 31, 1927, Serial No. 216,705, and in Great Britain February 28, 1927.

This invention relates to mechanism for operating the valves of internal combustion engines, and it has for its object the actuation of the valve in a manner which provides advantages not found in existing mechanisms.

I attain this end by the construction shown in the accompanying drawing in which:—Figure 1 is a broken view in side elevation, and Figure 2 is a broken view in plan.

In both views similar parts are marked with like numerals of reference.

On to the spindle 1 of the valve—which in the accompanying drawing is shown of the poppet type but which may be of any other type having a direct lifting action—is fixed a tappet 2 which slides in a bonnet guide 3 carried by the valve box 4 or any other convenient part of the engine. The tappet 2 is forked to carry a roller 5 which is mounted on a pin 6 carried by said fork and its forked ends 7, 7 are extended to give to the tappet a maximum of bearing surface. The bonnet guide 3 is also provided with two longitudinal slots 8 and 8 with which the fork of the tappet registers.

In advance of the guide 3 and in parallel relation to the pin 6 is a transverse shaft 9 on which is mounted the operating cam 10 which may be either of the reciprocating type formed on and operated by a lever 11 through a link 12 as shown in the accompanying drawing, or it may be of the rotating type. This cam engages the roller 6 and through the tappet 2 imparts the necessary motion to lift the valve against the action of springs 13 which operates to close it. These springs are conveniently arranged one on each side of the guide 3 and act between transverse extensions 14 of the pin 6 and fixed anchors 15 carried by the end of the said guide.

The shape of the cam 10 is such that the radius of its entrant end 16 is slightly less than the distance between the axis of the shaft 9 and that part of the cam surface adjacent to its acting or lifting surface 17, and the radius of the curvature of said acting or lifting surface is slightly greater than half the diameter of the roller 5.

Beneath the guide 3 is a box-like receptacle 18 which forms an oil bath into which the cam 10 dips at each reciprocation or revolution through the slot 8 in the lower

part of the guide as shown in dot and dash lines in Figure 1 and so operates to carry oil to the roller 5 the pin 6, the tappet 2 and its guide 3.

What I claim is:—

1. In a valve operating mechanism for internal combustion engines the combination with the valve, of a forked tappet carried by the stem of the valve, a fixed guide adapted to receive said tappet, slots in said guide with which the fork of the tappet registers, a transverse pin mounted in the forked part of the tappet, a roller mounted on said pin, springs operating between extensions of said transverse pin and fixed points on the guide, a transverse shaft mounted in bearings located in advance of said guide, and a cam mounted on said shaft and adapted to engage the roller carried by the tappet, the shape of the cam being such that the radius of its entrant part is slightly less than the distance between the axis of the shaft carrying the cam and that part of the cam surface adjacent to its lifting surface and that the radius of the curvature of said cam surface is slightly greater than half the diameter of the roller carried by the tappet.

2. In a valve operating mechanism for internal combustion engines the combination with the valve, of a tappet mounted on the stem of the valve which is slotted at its forward end, a fixed guide adapted to receive said tappet slots in said guide with which the fork of the tappet registers, a transverse pin mounted in the forked part of the tappet, a roller mounted on said pin, springs operating between extensions of said transverse pin and fixed points on the guide, a transverse shaft mounted in bearings located in advance of said guide, a cam mounted on said shaft and adapted to engage the roller carried by the tappet, the shape of the cam being such that the radius of its entrant part is slightly less than the distance between the axis of the shaft carrying the cam and that part of the cam surface adjacent to its lifting surface and that the radius of the curvature of said cam surface is slightly greater than half the diameter of the roller carried by the tappet, and an oil bath located below the guide of the tappet and in communication with said guide by the slot in its lower part.

THOMAS TOMNEY McILRAITH.
